UNITED STATES PATENT OFFICE

127,530

DESIGN FOR A BLADE FOR PAPER BOX OPENER

Lewis Walters, New York, N. Y.

Application March 14, 1941, Serial No. 99,599

Term of patent 14 years

To all whom it may concern:

Be it known that I, Lewis Walters, a citizen of the United States, residing at New York, in the county of New York and State of New York, have invented a new, original, and ornamental Design for Blade for Paper Box Opener, of which the following is a specification, reference being had to the accompanying drawing, forming a part thereof.

In the drawing:

I claim:

The ornamental design for a blade for paper box opener, as shown.

LEWIS WALTERS.
